APPARATUS FOR ASSEMBLING AEROSOL DISPENSING DEVICES

This invention relates to the production of aerosol dispensing devices.

More particularly, this invention relates to an improved apparatus for assembling the valve structure and the container in the production of aerosol dispensing devices such as those disclosed in U.S. Pat. Nos. 2,721,010, 3,001,524 and 3,301,306.

Still more particularly, this invention relates to an improved apparatus for aligning and holding down the valve structure during its assembly with the aerosol container by a crimping operation.

Accordingly, it is an object of this invention to provide an improved apparatus for aligning and holding down the valve structure during the aforementioned crimping operation.

While alignment and holddown procedures are presently used in the assembly of aerosol dispensing devices, they are generally inaccurate and result in a loose fit during the assembly procedure. This will often lead to leakage of the contents of the container after assembly. Accordingly, it is a further object of this invention to provide a more accurate assembly apparatus and procedure than that which is presently in use.

Other objects and advantages of this invention will become evident from the following description in conjunction with the accompanying drawings, in which:

FIG. 1 is a sectional view of the aligning and holding device of this invention and the aerosol valve and neck portion of the container to be assembled;

FIG. 2 is a sectional view of the aligning and holding device of FIG. 1 in engagement with the aerosol valve and container being assembled in which the aligning and holding device is partially depressed;

FIG. 3 is a sectional view of the aligning and holding device of FIG. 1 in engagement with the aerosol valve and container being assembled in which the aligning and holding device is fully depressed; and

FIG. 4 is a sectional view of the aligning and holding device of FIG. 1 in engagement with the assembled aerosol dispensing device.

Referring to FIG. 1, there is shown an alignment and holddown assembly generally designated 1 and the aerosol dispensing device generally designated 2 being assembled. The aerosol dispensing device 2 comprises a container 3 having a lip 4, an annular washer 5 of elastic material, such as rubber, a sealing ring 6 and a pump assembly 7 which is substantially as described in the aforementioned patents. Surrounding the pump assembly 7 is a metallic sleeve generally designated 8 having a cylindrical tubular portion 9 which has its interior diameter substantially equal to the exterior diameter of the lip 5 of the container so that the cylindrical portion fits closely about the exterior of the lip. The metallic sleeve 8 has a substantially radial portion 10 extended inwardly from the upper part of the cylindrical portion 9. The metallic sleeve 8 also has a cylindrical, tubular portion 11 extending upwardly a substantial distance above the radial portion 10. At the upper end of the cylindrical, tubular portion of the metallic sleeve 11, the sleeve turns inwardly to form a shoulder portion 12 that has a central aperture 13 through which extends the valve stem 14. This metallic sleeve 8 secures to the container 3 the pump assembly 7.

The alignment and holddown assembly 1 of this invention is utilized in the assembly of the aerosol dispensing device 2. This assembly comprises a holder 20, an alignment portion 21 and a holddown portion 22. The holder 20 is constructed of metal and has an upper cavity 23 and a lower cavity 24 which are connected by a round channel 25 in the center portion 26 of the holder 20. The holddown portion 22 comprises a metal holddown 27 and a metal ring 28. The outside surface 29 of the holddown 27 abuts the surface 30 of cavity 24. Holddown 27 has a radial shoulder 31 which extends outwardly from the

bottom edge of portion 32 of the holddown 27 to the uppermost edge of portion 33 of the holddown 27. The upper edge 34 of the ring 28 abuts the shoulder 31 of the holddown 27 and shoulder 35 of the alignment portion 21 while the bottom edge 36 of the ring 28 and the bottom edge 37 of the holddown 27 form a common pressure applying surface. An adjustable screw 38 is used to lock the holddown 27 into place and a washer 39 is used to insure a tight fit of the holddown 27 against the upper surface of the cavity 24.

- 10 The alignment portion 21 has an upper external edge 40 which is slidably engaged with the surface 41 of cavity 24. The upper portion of helical spring 42 surrounds the portion 43 of the screw 38 which protrudes into cavity 24 and the lower portion of helical spring 42 extends into upper recess 44 of the alignment means 21. The alignment means 21 has a lower cavity 45 which has a tapered portion 46 extending upwardly and inwardly from the lowermost edge of the outside portion 47 of the alignment means 21 to a narrow tubular recess 48 which is of a diameter which corresponds to that of the valve stem 14 of the pump assembly. Surface 47 of the alignment means 21 is slidably engaged with the inner surface 49 of the ring 28. The lowermost edge of alignment means 21 is prevented from extending below the bottom edges 36 and 37 of the holddown portion by the engagement of the shoulder 35 by the uppermost edge of the ring 28.

In operation, as each container and valve structure reaches the assembly station the holddown assembly 1 is automatically actuated and depressed thereby guiding the valve stem 14 into recess 45 as shown in FIG. 2. At this point the valve stem 14 is in engagement with the sides and bottom of the narrow tubular recess 48. As the holddown assembly 1 is further depressed the pressure exerted by the top of the valve stem 14 against the bottom of recess 48 forces the alignment means 21 upward into the cavity 24 against the pressure exerted by spring 42. 35 When the position shown in FIG. 3 is reached the spring 42 is compressed and surfaces 36 and 37 of the holddown assembly are exerting pressure evenly on the entire surface of the radial portion 10 of the metal sleeve 8. At this point crimping means (not shown) are actuated and crimp the lowermost extending portion 50 of the metal sleeve 8 tightly against the neck of the container as shown in FIG. 4. At this time the holddown assembly is retracted and returned to the position of FIG. 1 wherein the operating cycle is repeated.

Two important features of this invention are the accurate alignment of the valve structure due to the use of the improved alignment means 21 and the even application of pressure on the entire surface of the radial portion 10 of the metal sleeve 8.

I claim:

- 50 1. In an apparatus for assembling aerosol dispensing devices, the combination comprising:
a. means for aligning the valve structure of an aerosol dispensing device with the container, said means having a tapered portion extending upwardly and inwardly from the lowermost edge of said alignment means to a narrow tubular recess;
55 b. means for applying pressure evenly to the entire radial surface of a metal sleeve surrounding the pump assembly of said valve structure; and
c. means for imparting reciprocal vertical motion to said alignment and pressure applying means.
60 2. An apparatus as in claim 1 in which the narrow tubular recess has a diameter which is equal to or slightly larger than that of the valve stem of the aerosol device being assembled.
65 3. An apparatus as in claim 1 in which the means for applying pressure comprise a metal holddown and a metal ring.
4. An apparatus as in claim 3 in which the metal ring surrounds the outside portion of the alignment means and keeps said alignment means in place.
70 5. An apparatus as in claim 1 in which the alignment means is reciprocally moveable against the pressure of a helical spring.
